UNITED STATES PATENT OFFICE

2,591,593

HANDLE FOR CARTON CARRIERS

Lester S. Nolan, Pittsburgh, Pa.

Application July 13, 1949, Serial No. 104,427

2 Claims. (Cl. 229—52)

1

This invention relates to new and useful improvements in paper cartons for bottles and the like, and more particularly to the type having grips or handles for carrying the same; and it is among the objects thereof to provide a carton in which the grip or handle member is a portion of a partition which is normally contained within the carton and which may be extended from a wall of the carton to provide a projecting handle member.

Other objects of the invention will become more apparent from a consideration of the accompanying drawing, constituting a part hereof, in which like reference characters designate like parts, and in which:

Fig. 1 is a view in perspective of a carrier carton embodying the principles of this invention;

Fig. 2 is a top plan view thereof with the flaps open;

Fig. 3 is a cross sectional view taken along the line 3—3 of Fig. 2 as viewed from the right-hand side of the sheet; and

Fig. 4 is a side elevational view of a partition member having a handle portion by which the carton is transported.

With reference to the several figures of the drawing, numeral 1 designates a paper carton of relatively thick cardboard having cover flaps 2 and partition members 3, the carton in the drawing being partitioned for twelve compartments for beverage bottles or the like. The invention consists of the use of a partition 4 which may be of greater thickness than the partitions 3 and which is shown in detail in Fig. 4. It is provided with slots 5 and 6. Transversely disposed partitions 7 and 8 in the carton 1 are slotted at 9 and 10 to substantially half their depth for inserting the central partition member 4, and the space of the slots 5 and 6 permits displacement of the partition through a slot 11 at one side of the box as shown in Fig. 1, the partition 4 being provided with a grip or handle 13 having a cut-out portion 14. The slot 11 is slightly wider than the thickness of the partition member 4 and is provided with a cut-out portion 15 through which the grip 13 may be engaged by the thumb and forefinger to pull the partition out of the side of the box, leaving the handle 13 projecting as shown in Fig. 1.

The invention is to be used with sealed cartons so that the flaps 2 are glued shut. In shipping, the handle 13 is pressed inwardly to leave a smooth side surface which does not interfere with handling and stacking. When transported individually, the partition members 4 are displaced by pulling the handle 13 from the container to be gripped for carrying the carton.

It will be noted with reference to Figs. 2 and 3 of the drawing that when the handle projects from the wall of the carton the slotted edges 5

2

and 6 of the partition 4 engage the partitions 7 and 8 which in turn abut against the beverage bottles, designated by the numeral 16, so that the weight of the carton is distributed by the handle over the areas of the partitions 7 and 8, which in turn are held against displacement by the bottles 16. The only strain on the partition itself is in the longitudinal plane which prevents local stressing, bending or tearing of the heavy cardboard material.

It is evident from the foregoing description of the invention that beverage bottle containers having handles constituted by one of the partition members to be slidably into or out of position for carrying provide strong, durable and simple construction and facilitate the transportation of individual containers.

Although one embodiment of the invention has been herein illustrated and described, it will be evident to those skilled in the art that various modifications may be made in the details of construction without departing from the principles herein set forth.

I claim:

25 1. In a cardboard carton partitioned for beverage bottles or the like, a handle member consisting of a partition having slots interacting with the slots of cross partitions and having one end shaped to form a handle projected at right angles to the cross partitions, the slots of said handle partition being of a width to permit sliding the partition at right angles to the cross partitions a distance to project the handle, and said carton having a slot in a side through which the handle projects in its extended position.

30 2. In a paper carton for carrying beverage bottles and the like, a plurality of cross partitions forming individual spaces for the bottles, said partitions having slots extending halfway of their height to interact with the slots of transverse partitions and a central partition having an end projected at right angles to the cross partitions shaped to the form of a handle having slots interacting with the slots of its cooperating partitions, said slots being of a width to permit sufficient movement at right angles to the cross partitions to project the handle beyond the wall of the carton, a wall of said carton being slotted to permit the partition to extend therebeyond and having 35 rounded openings to permit insertion of the fingers in the carton to grasp the handle and withdraw the same from the carton.

LESTER S. NOLAN.
